UNITED STATES PATENT OFFICE.

GIUSEPPE MARATEA, OF BROOKLYN, NEW YORK.

BARREL HEAD.

Application filed February 24, 1925. Serial No. 11,355.

To all whom it may concern:

Be it known that I, GIUSEPPE MARATEA, a citizen of the United States, residing at Brooklyn, in the county of Kings and State 5 of New York, have invented certain new and useful Improvements in Barrel Heads, of which the following is a specification.

This invention relates to an improved barrel head and seeks, among other objects, 10 to provide a head embodying a pair of mating doors which may be separately opened to afford access to the barrel.

The invention seeks, as a further object, to provide a head wherein the doors will 15 normally close the head tightly and wherein one of the doors will be provided with a drain opening so that the barrel may, if desired, be drained of any liquid therein without the necessity of opening the doors.

20 And the invention seeks, as a still further object, to provide a head adapted for general use in connection with barrels as now constructed.

Other and incidental objects will appear 25 hereinafter.

In the accompanying drawings:

Figure 1 is a perspective view showing my improved head in position in a barrel.

Figure 2 is a sectional view on the line 30 2-2 of Figure 1, looking in the direction indicated by the arrows.

Figure 3 is a sectional view on the line 3-3 of Figure 1, looking in the direction indicated by the arrows.

35 In accordance with the present invention, the barrel head comprises a pair of like side sections 10 and extending transversely between the sections therebeneath is, as particularly shown in Figure 3 of the drawings, 40 a cross cleat 11 rigidly connecting the sections with each other. This cross cleat may be screwed or otherwise secured to the sections and is of a length to extend throughout the major portion of the width thereof so 45 as to provide a reinforcing brace for said sections. In the drawings, I have shown the head in position in a barrel 12. At its adjacent end the shell of the barrel is provided with an internal beveled seat 13 while 50 the peripheral edges of the sections 10 are beveled to fit in said seat, and surrounding the barrel is a hoop 14 binding the head in position, the loop lying flush with the adjacent end of the barrel.

55 As particularly shown in Figure 1, the

straight parallel inner edges of the sections 10 are beveled away from each other toward the lower sides of said sections and 60 slidable between the sections is a pair of mating doors 15 and 16, the side edges of 60 which are beveled to slidably fit the beveled edges of the sections. At their inner ends, the doors are, as particularly shown in Figure 2, provided with mating beveled edges 65 17 while at their outer ends, the edges of the doors are curved to conform to the peripheral edges of the sections 10, and formed in the barrel at the ends of the doors are notches 18 through which the doors may 70 be drawn outwardly. Pivotaly mounted upon the doors near the outer ends thereof are buttons 19 connected with the doors by pivot bolts 20 and preferably the nuts at the upper ends of the bolts are counter-sunk 75 in the buttons so that said nuts will not form obstructions at the upper sides of the buttons. The buttons are of such length that, as shown in Figure 1, when arranged across the doors, the ends of the buttons 80 will overhang the sections 10 of the head a considerable distance so as to have a firm bearing against the upper sides of the sections for rigidly and tightly holding the doors closed. Formed in the door 15, near 85 its outer end, is a medially disposed drain opening 21.

As will now be seen in view of the foregoing, the button of the door 15 may be turned to extend longitudinally of the door, 90 when said door may be drawn outwardly from between the sections 10 of the barrel head and thus opened without the necessity of molesting the door 16. In like manner, the door 16 may be opened without the necessity of molesting the door 15, but, if desired, 95 both doors may, of course, be shifted outwardly to open position and may also, if desired, be entirely removed. The drain opening 21 is provided in order that the barrel 100 may be drained of any liquid therein without the necessity of opening either of the doors.

Having thus described the invention, what I claim is:

1. A barrel head including spaced side sections, a rigid bar extending across the space between said sections intermediate the ends thereof and having its end portions firmly secured to the underfaces of the sections, and a closure slid into the space between said sections with its side edge por- 110

tions in underlying relation to the adjacent side edges of said sections, said closure resting upon said bar when in a closed position.

2. A barrel head including spaced side sections, a rigid bar extending across the space between said sections intermediate the ends thereof and having its end portions firmly secured to the under faces of the sections, a closure slid into the space between said sections with its side edge portions in underlying relation to the adjacent side

edges of said sections, said closure resting upon said bar when in a closed position, and a latch bar pivoted upon the upper face of said closure and adapted to be turned to extend transversely thereof with its end portions overlying said sections and frictionally engaging the outer faces thereof to releasably retain the closure in a set position. 15

In testimony whereof I affix my signature.

GIUSEPPE MARATEA. [L. s.]
